TYPEWRITING AND LIKE MACHINE

Henry A. Heinrich, Middletown, Conn., assignor
to Remington Rand Inc., Buffalo, N. Y., a cor-
poration of Delaware

Application September 26, 1938, Serial No. 231,625

13 Claims. (Cl. 197—31)

My invention relates to typewriting and like machines and more particularly to means for preventing rebound of the type bars and associated parts from their normal positions of arrest 5 in the return thereof after each actuation.

One of the main objects of my invention, generally stated, is to provide simple and highly effective means of the character specified which will offer no resistance to the actuation of the 10 type actions, thereby affording a light touch on the printing keys.

Another object of my invention is to provide means of the character specified which are noiseless in their operation.

15 A further object of my invention is to provide such anti-rebound means which may be readily combined with existing type actions without modifying, or materially modifying, the existing structural features thereof except to include 20 therein features of the present invention as a substitute for the anti-rebound devices previously employed.

To the above and other ends which will hereinafter appear, my invention consists in the features of construction, arrangements of parts and combinations of devices set forth in the following description and particularly pointed out in the appended claims.

In the accompanying drawings wherein like 30 reference characters indicate corresponding parts in the different views:

Fig. 1 is a detail, fragmentary, side elevation showing a type action equipped with the anti-rebound device of my invention, the view showing 35 the parts as they appear in normal position.

Fig. 2 is an enlarged, detail, fragmentary view of a portion of the same showing the parts in side elevation in the normal position.

Fig. 3 is a like view of the same but showing 40 the parts in the actuated position.

Fig. 4 is an enlarged, detail, fragmentary, transverse sectional view taken on the line 4—4 of Fig. 2 and looking in the direction of the arrows at said line.

45 I have shown my invention in the present instance embodied in a type action of a No. 6 or No. 10 Remington Noiseless machine in which the devices of my invention may be readily incorporated without modifying, or materially modifying, the 50 existing structural features thereof. It should be understood however, that the invention is not restricted to embodiment in such machines, but may be used in typewriting and like machines generally, wherever found available.

55 I have disclosed only a single type action in the

accompanying drawings, that being sufficient to arrive at an understanding of my invention in its combination therewith. Such type actions are disclosed in the patent to Going No. 1,573,544 dated Feb. 16, 1926.

In the present instance I have dispensed with the anti-rebound devices disclosed in the patent to Going No. 1,604,640 dated Oct. 26, 1926, which have been employed in Remington No. 6 and No. 10 Noiseless machines and have substituted therefor the anti-rebound devices of the present invention.

The type actions per se are, or may be, of the usual construction and will first be described.

Referring to Fig. 1 it will be observed that each 15 type bar 10 carries four types 11, 12, 13 and 14, and is pivotally supported on guide links 15 and 16. The lower end of the link 16 is pivoted at 17 on an arm 18 adjustably secured to a supporting bracket 19. The lower end of this link 16 is pivoted at 20 to a bellcrank lever 21 pivoted at 22 to the supporting bracket 19. The other arm of the lever 21 is pivoted to a link 23 which in turn is pivotally connected to a sub-lever 24 pivoted at 25 to the bracket 19.

The actuating means for the type bar, in the present instance, comprises the usual toggle members 26 and 27 pivotally united at 28. The toggle member 27 is pivoted at 29 to the supporting bracket 19.

A second toggle comprises an arm or member 31 and a pivotally connected actuating lever 32, the arm 31 being pivoted at 33 to the member 27 of the first toggle. The lever 32 comprises two matched members fixedly united and maintained 35 spaced apart and arranged on opposite sides of the bracket 19, as shown in Fig. 4. A weight or momentum accumulator 34 is, in the present instance, fixed to and forms an extension of the toggle member 31.

The actuating lever 32 is pivoted at 35 on the supporting bracket 19 and is in the nature of a bellcrank lever having on the substantially horizontally disposed arm thereof a curved contact face 36. This contact face is of sufficient width 45 to coact with the curved contact edge of the sub-lever 24 and also to coact with a curved contact edge of a second corresponding sub-lever 37. The sub-lever 24 has a depending link 38 pivoted thereto, which link in turn is pivoted at its lower end, as at 39, to a key lever 40. In a like manner 50 a depending link 38a constitutes the connection between the sub-lever 37 and a second key lever 41.

Each key lever 40 and 41 has a returning spring 55

42 connected thereto, whereas a single returning spring 43 is anchored at one end to the bracket 19 and is connected at its other end to a pin 44 by which a universal-bar actuating-yoke 45 is pivoted to the actuating lever 32. The spring 43 is effective to return the lever 32 and the parts connected therewith to normal position.

In the operation of the type action a depression of the key lever 41 will actuate the sub-lever 37 causing a straightening of the toggles 26, 27 at which time the links 15 and 16 will turn on their respective pivots 20 and 17; the bellcrank 21 at this time remaining fixed. The effect of this is to produce a noiseless pressure imprint from one or 15 another of the types 13, 14, depending on whether the platen 46 is in the upper or lower case position.

If on the other hand the key lever 40 is depressed then the type bar will be actuated as before except that the actuation of the sub-lever 24 will cause the bellcrank 21 to be shifted as shown in Fig. 3, thereby lowering the pivot 20 and causing the type bar to take a different path of travel to print from one of the types 11, 12 depending 25 on the position of the platen.

I will now describe the means of my present invention which coact directly with a part of each type action in the return movement thereof to normal position to prevent rebound of the parts 30 from such normal position of arrest.

An anti-rebound member, angular lever or device 47, preferably made of sheet metal, is mounted to turn on a headed shouldered pivot 48 riveted or otherwise secured to each hanger 19. 35 As shown in Fig. 4, the hub-like portion 47a of each member 47 is offset laterally from the main body portion thereof and the member as a whole is received between the two matching sides which go to make up the actuating lever 32. The pivot 40 48 is rearwardly offset from the main body of the member 47, so that the preponderance of weight of the member is forward of the pivot 48 and tends by gravity to turn the member 47 in an anti-clockwise direction. The depending arm of 45 the member 47 is provided with a laterally projecting lug or contact 49 that bears against the forward edge of one of the matching side members that make up the lever 32. The upper edge 50 of the member 47 is curved and when the parts 50 are in normal position as shown in Fig. 2, this curved edge corresponds substantially to an arc taken around the pivot 35 of the lever 32 as a center. A pin or contact 51 is riveted to one of the matched members which constitute the lever 32 and projects inward therefrom and normally 55 contacts with the curved edge 50.

From the foregoing description, it will be understood that an actuation of the lever 32 by a depression of either key lever 40, 41 to bring about 60 a printing movement of the associated type bar, will cause the upright part of the lever 32 to move rearward free from any resistance by the anti-rebound device 47. At this time the force of gravity of said device will cause it to follow the 65 upright arm of the lever 32, due to the direct engagement of the lug 49 with the forward edge of said lever. During this movement of the anti-rebound device the curved edge 50 thereof is lowered and is maintained free from an engagement 70 with the pin or contact 51.

After the printing operation and during the return of the type bar and the parts connected therewith to the normal position of arrest, the lever 32 engaging the lug 49 will positively 75 turn the member 47 against the force of gravity

thereof. When the parts reach the normal position of arrest, the curved edge 50 of the anti-rebound device will be forced into engagement with the contact 51, thereby exerting a force that is directed lengthwise of the upright arm of the lever 32 against its fixed pivot 35, thus preventing a rebound of the lever 32 and the parts controlled thereby. As the parts are operated from normal position there is freedom of contact between the curved edge 50 and the pin 51 and the type action is free from obstruction or resistance by the anti-rebound device 47. This is a highly important factor as the use of the anti-rebound means adds nothing whatever to the force required to operate the type action, but on the other hand adds the force of gravity of the anti-rebound device to assist in the printing movement of the type bar, thereby providing a very light touch on the printing keys. Moreover, the anti-rebound device 47 constituting the only means for limiting the return movement of the lever 32 and the parts connected therewith there is substantially no noise produced in the arrest thereof and in the operation of the anti-rebound means, which is another important factor.

It will be observed that the anti-rebound device 47 is in the nature of an angular lever that has a three-point engagement, one point at its pivot 48, a second point between the lug 49 and the actuating lever 32, and the third point between the curved edge 50 and the contact 51. It will be observed moreover, that these three points of engagement are arranged at three points of a triangle.

It will be understood that the greater the force exerted to return the type bar and connected parts to normal position, the greater will be the momentary grip between the curved edge 50 and the contact 51 and the greater therefore will be the resistance against rebound.

It will be seen moreover, that by causing the lug 49 to engage the lever 32 near the pivot of the latter that a slight movement only of the anti-rebound device is effected and that the construction is such that this slight movement is all that is required to effectively prevent rebound of the type bar and connected parts. By maintaining a constant and direct engagement between the lug 49 and the lever 32 no noise is produced in the operation of the anti-rebound device.

By making the anti-rebound device of a single piece mounted as shown I am enabled to produce at little expense a highly efficient means for purposes stated and such means may be readily added to existing type actions without modifying, or materially modifying, the existing structural features thereof.

While I have described in detail one form of anti-rebound means embodying my invention in its cooperation with one form of type action, it should be understood that various changes may be made without departing from my invention as it is defined in the accompanying claims.

What I claim as new and desire to secure by Letters Patent is:

1. In a type action, the combination of an actuating member, a support therefor, a returning spring for said actuating member, and anti-rebound means for preventing the rebound of said actuating member from the position of arrest in its return movement to normal position, said anti-rebound means comprising a contact on said actuating member, an engaging member

- mounted on said support for upward movement transversely of the direction of movement of said actuating member and into engagement with said contact and for downward movement by gravity out of engagement therewith, and means actuated by said actuating member in the return movement thereof to normal position to thus move said engaging member into engagement with said contact and arrest said actuating member.
5. In a type action, the combination of supporting means, an actuating member mounted on said supporting means, and anti-rebound means for preventing the rebound of said actuating member from the position of arrest in its return movement to normal position, said anti-rebound means comprising a contact on said actuating member, an engaging member mounted on said supporting means for upward movement transversely of the direction of movement of said actuating member into engagement with said contact and downward movement by gravity out of engagement therewith, and means actuated by said actuating member in the return movement thereof to normal position to thus move said engaging member into engagement with said contact.
10. In a type action, the combination of supporting means, an actuating member mounted on said supporting means, and anti-rebound means for preventing the rebound of said actuating member from the position of arrest in its return movement to normal position, said anti-rebound means comprising a contact on said actuating member, an engaging member mounted on said supporting means for movement transversely of the direction of movement of said actuating member into engagement with said contact, and means actuated by said actuating member in the return movement thereof to normal position to thus move said engaging member into engagement with said contact.
15. In a type action, the combination of an actuating member, a support therefor, a returning spring for said actuating member, and anti-rebound means for preventing the rebound of said actuating member from the position of arrest in its return movement to normal position, said anti-rebound means comprising a contact on said actuating member, an engaging member mounted on said support for movement into engagement with said contact and for movement by gravity out of engagement therewith, and means actuated by said actuating member in the return movement thereof to normal position to thus move said engaging member into engagement with said contact and arrest movement of said actuating member under the force of said returning spring.
20. In a type action, the combination of supporting means, an actuating member mounted on said supporting means, and anti-rebound means for preventing the rebound of said actuating member from the position of arrest in its return movement to normal position, said anti-rebound means comprising a contact on said actuating member, an engaging member mounted on said supporting means for movement upward into engagement with said contact and downward by gravity out of engagement therewith, and means actuated by said actuating member in the return movement thereof to normal position to thus move said engaging member into engagement with said contact.
25. In a type action having a key-controlled member, supporting means therefor, a returning spring for said type action, and anti-rebound means for arresting the return movement of said key-controlled member to normal position comprising a stop on said key-controlled member, a stop engaging member mounted on said supporting means for movement into engagement with said stop on the key-controlled member and for movement by gravity out of engagement therewith, and means actuated by said key-controlled member in the return thereof to normal position under the force of said returning spring to thus move said stop engaging member into effective engagement with said stop on the key-controlled member.
30. The combination of a type action having a key-controlled member, supporting means therefor, and anti-rebound means for arresting the return movement of said key-controlled member to normal position comprising a stop on said key-controlled member, a stop engaging member mounted on said supporting means for movement transversely of the direction of movement of said key-controlled member into engagement with said stop, and means actuated by said key-controlled member for thus moving said stop engaging member into engagement with said stop.
35. The combination of a type action having a key-controlled member, a support therefor, and anti-rebound means for arresting the return movement of said key-controlled member to normal position comprising cooperating stops on said key-controlled member and said support, one of said stops being movable transversely of the direction of movement of said key-controlled member and into engagement with the other of said stops, and means actuated by said key-controlled member for thus engaging said stops.
40. The combination of a type action having a key-controlled member, a support therefor, and anti-rebound means for arresting the return movement of said key-controlled member to normal position comprising cooperating stops on said key-controlled member and said support, one of said stops being mounted for movement into engagement with the other of said stops, and means actuated by said key-controlled member for thus engaging said stops.
45. In a type action including a support and a pivoted member mounted thereon, the combination of a stop on said pivoted member, a stop movable on said support in a direction substantially transversely of the direction of movement of said pivoted member and into engagement with said stop on the pivoted member, and means controlled by the movement of said pivoted member to normal position for thus moving said stop on the support into engagement with said stop on said pivoted member, whereby the return movement of the pivoted member is arrested and the returning force thereof is directed transversely of the pivotal axis of the pivoted member.
50. The combination of a type action including an actuating member and a support therefor, cooperating stops on said actuating member and said support, the stop on said support being movable substantially transversely of the direction of movement of said actuating member and into engagement with the stop on said actuating member, and means actuated by said actuating member in the return thereof to normal position to thus move the stop on said support into engagement with the stop on said actuating member.
55. The combination of a type action including an actuating member and a support therefor, cooperating stop means on said actuating member and said support, one of said stop means being
60. The combination of a type action having a key-controlled member, supporting means therefor, a returning spring for said type action, and anti-rebound means for arresting the return movement of said key-controlled member to normal position comprising a stop on said key-controlled member, a stop engaging member mounted on said supporting means for movement into engagement with said stop on the key-controlled member and for movement by gravity out of engagement therewith, and means actuated by said key-controlled member in the return thereof to normal position under the force of said returning spring to thus move said stop engaging member into effective engagement with said stop on the key-controlled member.
65. The combination of a type action including an actuating member and a support therefor, cooperating stop means on said actuating member and said support, one of said stop means being
70. The combination of a type action including an actuating member and a support therefor, cooperating stop means on said actuating member and said support, one of said stop means being
75. The combination of a type action including an actuating member and a support therefor, cooperating stop means on said actuating member and said support, one of said stop means being

movable substantially transversely of the direction of movement of said actuating member and into engagement with the other of said stop means, and means actuated by said actuating member in the return thereof to normal position to thus engage said cooperating stop means.

13. The combination of a type action having a support, a pivoted actuating lever on said support, and anti-rebound means for preventing rebound of said lever in the return movement thereof to normal position, said anti-rebound

means comprising a stop on said actuating lever, a stop engaging member pivotally mounted on said support for movement transversely of the pivotal axis of said actuating lever and into and out of engagement with said stop on the actuating lever, and an arm on said stop engaging member extending into the path of movement of said actuating lever to normal position for thus moving the stop engaging member into effective engagement with said stop on the actuating lever. 10

HENRY A. HEINRICH.
